(57) **CLAIM**

The ornamental design for an internally illuminateable device, as shown and described.

DESCRIPTION

FIG. 1 is a perspective view of an internally illuminateable device showing my new design in a non-illuminated state; FIG. 2 is a top plan view thereof;

FIG. 3 is a front elevation view thereof;

FIG. 4 is a left side elevation view thereof;

FIG. 5 is a right side elevation view thereof;

FIG. 6 is a rear elevation view thereof;

FIG. 7 is a bottom plan view thereof; and,

FIG. 8 is a front elevation view similar to that of FIG. 3, shown in an internally illuminated state with the radially extending lines representing illumination.

The broken lines shown in FIG. 7 illustrate portions of the internally illuminateable device which form no part of the claimed design. The broken lines in FIG. 1 illustrate a neck strap which forms no part of the claimed design. The broken lines in FIGS. 2-6 and 8 illustrate portions of a neck strap which form no part of the claimed design. The surface texture on the device in FIGS. 1 through 8 is shown to indicate a reflective, sparkling surface appearance.
